UNITED STATES PATENT OFFICE.

RENÈ GOUIRAND AND AUGUSTE PACHE, OF NEW YORK, N. Y.

CLAMP.

Application filed May 19, 1925. Serial No. 31,283.

To all whom it may concern:

Be it known that we, RENÈ GOUIRAND and AUGUSTE PACHE, a citizen of the United States and a citizen of Switzerland, respectively, both residing at New York city, county and State of New York, have invented a certain new and useful Clamp, of which the following is a specification.

This invention is a clamp and more particularly a clamp of the type embodying a suitable clamping member cooperating with a flexible band which may be placed under tension to effect the clamping operation. The invention is adapted for many uses, but will be hereinafter described in the interest of clearness in connection with its employment as a hose clamp.

In its preferred practical form, the invention embodies a clamping or tie member to which one end of a flexible band is adapted to be secured and said tie member is provided with a passage or slot through which the other end of the band is adapted to be passed. A suitable key, preferably a cotter pin, is utilized to place the band under tension and the slot or passage through which the band extends is shaped to effect an automatic locking of the band against loosening.

A particularly important feature of the present invention consists in the automatic locking of the band to which we have referred, the tie member being so configurated that the mere act of placing tension upon the band will form on the band locking abutments adapted to cooperate with the tie member in such manner that when pressure is removed from the key, the band will be automatically maintained against inadvertent release, so that if desired the key may be actually withdrawn and will leave the parts in locked position. An important consideration in this regard is in the fact that no extraneous locking means is required. The idea of locking the clamping band after it has been placed under tension has been heretofore accomplished, an example of such a construction being illustrated in the patent to Quemard, No. 1,461,290. In this pat-

ent, the band is pulled tight and is thereafter locked in position by extraneous means and more particularly a set screw.

Our device, in contradistinction, employs no extraneous means and does not, as many other prior patents do, depend upon friction to maintain the band against unlocking. We provide a positive lock which is automatically produced by the mere act of tightening the band, so that when the tightening operation is completed, the lock is ready to assume its functions. This is a pronouncedly novel feature in this art.

Features of the invention, other than those adverted to, will be apparent from the hereinafter detailed description and claims, when read in conjunction with the accompanying drawings.

The accompanying drawings illustrate different practical embodiments of the invention, but the constructions therein shown are to be understood as illustrative, only, and not as defining the limits of the invention.

Figure 1 is a perspective view illustrating the clamping or tie member embodying our invention.

Figure 2 is a plan view of the construction.

Figure 3 shows the device in place upon a pipe.

Figure 4 is an edge view of the construction shown in Figure 3.

Figure 5 is a face view of a modified form of construction.

Figure 6 is a side elevation of the construction of Figure 5.

Figure 7 is an end view of such device looking from the left hand side of Figure 6; and,

Figures 8, 9 and 10 are fragmental diagrammatic views illustrating the manner in which the locking operation is effected, Figure 8 being taken on the line 8-8 of Figure 4 and Figure 9 being taken on the line 9-9 of said figure.

In constructing the clamp of this invention in its preferred form, we preferably stamp the tie member from sheet metal and thereafter bend it into the form best shown

in Figures 1 and 2 of the drawings. In this form, it is substantially of triangular cross section, the base 1 being formed integral with the shorter leg 2, while the longer leg 3 is slightly curved longitudinally and projects beyond the free edge of the base as is clearly shown in Figure 1.

At substantially the base of the leg 2 a tongue 4 is stamped out to provide an opening 5 through which a band may be passed and formed in the leg 3 is an opening 6 substantially juxtaposed with the opening 5, but preferably slightly larger in height. Particular attention is called to the fact that the top edge 7 of the opening 6 is curved after the manner of an arch, and said opening also preferably slightly tapers in an upward direction, as clearly shown in Figures 1 and 2.

In utilizing this tie member as a part of the clamp, one end of a metal band 8 is passed through the opening 6 from the outside thereof and is returned upon itself beneath the free edge of the leg 3 for an appreciable distance as to the point 9 in Figure 4. The band is then wrapped one or more times about the object 10 to be clamped, two complete turns being shown in Figure 4, and each turn passes through the openings 5 and 6, as shown in this figure.

After the desired number of turns have been obtained, a suitable key is brought into cooperation with the free end of the band which is thereupon rolled, as shown also in Figure 4. For the purpose of illustration, I have shown the key in Figure 3 as in the form of a cotter pin 11, although, if desired, a square key or any other suitable form of key may be employed. In Figure 6, a square key 11^a is shown. When a cotter pin is employed, the free end of the band is introduced between the arms of the pin and the pin is thereupon rotated to roll up the band as illustrated in Figure 4.

At the commencement of the rolling operation, it will be found that the band rolls very easily and such would be the case until a sufficiently large portion of the band has been rolled to bring the roll or coil 12 thus formed against the outer face of the leg 3. Further rolling of the band will manifestly place the band under tension and as the rolling operation continues, the tension will become greater to the end that the band may be drawn tightly about the object 10.

As the tension on the band increases, the automatic locking means of this invention comes into operation and the manner in which the locking is effected will now be described.

The band, in its natural form, is flat, but as it is drawn into the coil 12, it is pressed tightly against the arched or curved edge 7 of the opening 6. A suitable implement, such as a nail, introduced through the eye

of the cotter pin, makes it possible to exert great power to rotate this pin and this great power is applied to draw the band through the opening 6 and add additional portions of the band to the coil. The relatively great tension serves to deform the band as it is drawn through the opening 6, so that as each part of the band passes through the opening it is caused to transversely conform to the curvature of the edge 7. The coil or roll 12 is substantially cylindrical at the commencement of the tension operation and consequently there results by this deformation of the band a slight stretching of the marginal edges. Thus as each marginal edge passes through the opening 6, it leaves the edge 7 in slightly stretched condition to be thereafter immediately wound upon the substantially cylindrical coil or roll 12. The conformation of the roll in practice causes the inner concave formation of the band to be reversed, so that it becomes exteriorly concaved beyond the edge 7, and is wound upon the roll in this form to produce a roll which is longitudinally slightly concave as is clearly apparent from Figure 3.

The result of this operation is that the reversal of the transverse configuration of the band occurs as soon as it leaves the edge 7, and there is accordingly produced a reaction which draws the coil close to the edge 7 and produces at either margin of the band a tendency of the edge 7 to bite into the band while the band is simultaneously formed adjacent its margins into pronounced abutments.

This operation will be apparent from Figures 8 and 9. Figure 8 is a section on the line 8—8 of Figure 3, and it will be noted that this section is taken adjacent the marginal edge of the band. In this view, the line 8^a shows the contour of the band at its longitudinal medial line and it will be noted from this figure that the band is appreciably distorted transversely to conform with the edge 7. The pronounced biting action of the edge 7 into the marginal portion of the band is here apparent and the abutment which results is designated 14, it being understood that this action will occur at both marginal portions of the band.

Figure 9 shows a section at the medial line of the band while the line 8^b shows the contour at the marginal edge of the band. At the center of the band, there is little, if any, stretching and the biting action at this point is therefore not so pronounced, although a relatively pronounced abutment 14^a is produced at this point.

Figure 10 shows the abutments 14 which are actually formed in the band through a deformation of such band by the arched shaping of the edge 7, and it will be manifest that when the band is deformed as shown, it is effectually locked against any

tendency to pull loose even when the tension on the key is relieved, so that, in practice, it is found entirely feasible after the desired tension has been obtained to actually re-
5 move the key. We wish it understood, however, that it is within the purview of this invention to therefore lock the band by bending into divergent relation one or both of the free ends of the arms of the cotter pin, 10 as shown in dotted lines in Figure 3, the purpose being to leave the key in position with the supplemental lock. This supplemental lock is, in practice, however, not necessary as the automatic locking feature 15 which we have described is entirely effective in locking the parts in position.

In the manufacture of devices such as have been described, we preferably utilize in the formation of the tie member, material which, while sufficiently strong to withstand the forces to which it is subjected, yet will yield sufficiently in predetermined directions to bring about a novel and highly efficient mode of operation of the tie member when placed under the action of these forces. For example, it will be noted that when a band is placed under appreciable tension, this tension will be borne mainly by the leg 3, and such tension will be exerted 20 against the exterior substantially flat side of the leg. Such tension will have a tendency to react upon the tie member in two distinct directions. That is to say, it will have a tendency to act in the direction of the arrow 15 in Figure 4 to force the base 1 tightly against the object 10, and by such force will simultaneously effect a slight bending of the leg 3 to render its outer surface more or less concave. The combined 25 result of these forces causes the leg 3 to be pressed tightly against the free edge 16 of the base 1 which thereupon serves as a support for this leg and precludes further appreciable bending. At the same time, both 30 the base 1 and the projecting tongue 4 are bent by the band into conformity with the object 10.

The result is as shown in Figure 4, where-
50 in it will be apparent that there is a prac-
tically unbroken bridge at the bottom of the tie member extending from the free edge of the tongue 4 to the free edge of the leg 3. Inasmuch as the entire remainder of the circumference of the article 10 is uncom-
55 passed by the band, it therefore follows that the clamping action of the device will be uniform and positive throughout the entire circumference of the article 10, and there will be absolutely no tendency of the article 10 to crimp at any point in its circum-
60 ference as is so frequently the case in hose clamps now in common use.

In the preferred practical form of the invention, the tie member is constructed from 65 sheet metal, although for very heavy work,

said member may be in the form of a casting. In Figures 5 to 7 of the drawings, a modified form of the invention as it might be efficiently made in a casting is illustrated. In this showing, the tie member comprises 70 a base 17 provided intermediate its ends with an extending transverse bead 18, through which is formed a slot 19. The forward face 20 of the bead is concave to conform to the shape of the roll 12^a and the slot 75 19 is flared upwardly in the direction of the face 20 to intersect therewith in an arch-like edge 21, shown best in Figure 7. This edge 21 corresponds in function to the edge 7 of the other construction and operates in 80 the same manner. The base may be provided with a slot 22 for attachment of one end of the band, though, if desired, the band may be made to encircle the entire base instead of passing it through the slot 85 22, this arrangement being optional. The cast construction is of course not resilient, so that the particular mode of operation with reference to conformation of the device to the article to be clamped, is not present in the cast construction. Otherwise, the two arrangements function in substantially the same manner, and both provide 90 the efficient lock to which we have referred.

In conclusion, we wish to call attention to 95 the fact that when the leg 3 is drawn against the free edge 16 of the base, said edge engages with the bend of the band as shown at 23 in Figure 4 and tightly grips such bend so that it cannot possibly slip. The anchored end of the band is thus also locked 100 against inadvertent release.

It is also to be noted that as the band passes over the curved edge 7, it is distorted 105 in one direction and as it is rolled upon the roll, this distortion is reversed making the outside surface of the band adjacent the roll concave. This concavity serves to reinforce the band and conform and hold the locking abutments against release.

The method of locking a band as hereinbefore described also forms part of this invention.

The accompanying drawings illustrate the invention in the preferred practical forms, 115 but the invention is to be understood as fully commensurate with the appended claims.

Having thus fully described the invention, what we claim as new and desire to secure by Letters Patent is:

1. A clamp embodying a band, a tie member adapted to be secured to one end of the band and provided with an opening through which the other end of the band is adapted 125 to be passed and thereafter rolled, said opening being shaped to transversely distort the band during its passage therethrough for the purpose of precluding inadvertent retrograde movement of the band.

2. A clamp embodying a band, a tie mem-

ber adapted to be secured to one end of the band and having an opening through which the other end of the band is adapted to be passed and thereafter rolled, said opening having a curvilinear contour, whereby the rolling of the band to place it under tension will draw the band over such curvilinear contour and distort it sufficiently to effectually lock the band against inadvertent loosening.

3. A clamp embodying a band, a tie member associated with one end of the band and provided with an opening having a curved edge, the free end of the band being adapted to be passed through the opening and thereafter rolled to place the band under tension, and a suitable key for rolling said band, the tie member being shaped to force the band against said curved edge when placed under tension for the purpose of distorting the band and locking the band against retrograde movement.

4. A clamp embodying a band, a tie member associated with one end of the band and having an opening through which the opposite end of the band is adapted to be passed, said opening being provided with a curved edge, and means operable upon the free end of the band beyond the curved edge for placing the band under tension and simultaneously drawing it against said edge for the purpose of deforming the band to lock it under tension.

5. A clamp embodying a band, a tie connected to one end of the band and provided with an opening through which the other end of the band is adapted to be passed, means positioned beyond the opening and cooperable with the free end of the band to draw the band through the opening and place it under tension, said opening being configurated to deform the band during its passage therethrough to thereby preclude inadvertent retrograde shifting of the band.

45 6. A clamp embodying a band, a tie member secured to one end of the band, and of substantially triangular cross section, said tie member being provided with an opening having a converging edge at its mouth and through which opening the other end of the band is adapted to be passed, and thereafter rolled, to place the band under tension and force the band into gripping relation with the converging edge of the opening.

55 7. A clamp embodying a sheet metal tie member of substantially triangular cross section, one leg of which is longer than the other and the base of which forms a continuation of the shorter leg and the longer leg of which extends beyond the free edge of the base, a band secured at one end to the longer leg and both of which legs are provided with openings through which the other end of the band is adapted to be passed and thereafter rolled and the opening in one of

said legs converging towards the apex of the tie member.

8. A clamp embodying a sheet metal tie member of substantially triangular cross section having apertured legs of unequal length, 70 and a base forming a continuation of the shorter leg, a band having one end looped through an aperture in the longer leg and the other end of the band passed through apertures in both of the legs, and means for 75 rolling the free end of the band to place the band under tension and draw it tightly against the edge of the opening of the longer leg, said opening having a converging edge adapted to distort the band and effect automatic locking of the band at the edge of the opening and the tension on the band being sufficiently great to force the longer leg in the direction of the free edge of the base 80 sufficiently to engage said free edge with the loop portion of the band and lock said looped end of the band against slipping.

9. A clamp embodying a band, a tie member anchored to one end of the band and also having an opening through which the other end of the band is passed, said opening having a converging edge, and a key 85 cooperating with the free end of the band for rolling that portion of the band beyond the opening, whereby the band is drawn 90 against the converging edge and distorted to form shoulders in the band beyond said edge, which shoulders engage with said edge 95 and lock the band under tension, and the key being of sufficient length to project beyond the rolled portion of the band and being bent laterally to preclude unrolling of the rolled portion of the band, and to further lock the band under tension.

10. The herein described method of locking a band under tension which consists in drawing a flat metallic band under tension over a non-conforming edge by a force acting in a direction to draw the band tightly against 105 said edge, thus distorting the normal transverse shape of the band whereby locking abutments are produced thereon, which abutments cooperate with said edge to have locking engagement therewith for the purpose 110 of maintaining the band under tension.

11. The herein described method of locking a band under tension which consists in drawing a flat metallic band under tension over an edge which is shaped out of conformity to the normal transverse shape of the band and sharply deflecting the band beyond said edge to effect a distortion of the band, thus automatically forming in it abutments which have locking engagement with the edge.

12. The herein described method of locking a band under tension which consists in drawing a flat metallic band over a non-conforming edge by a force acting in a direction to draw the band tightly against said edge for 120

the purpose of distorting the band to form therein a positive lock.

13. The herein described method of locking a band under tension which consists in drawing a flat metallic band under tension over an edge shaped to distort the transverse cross section of the band in one direction and simultaneously reversing the distorted cross

section of the band beyond said edge to form in the band abutments adapted for locking engagement with said edge. 10

In testimony whereof we have signed the foregoing specification.

RENÈ GOUIRAND.
AUGUSTE PACHE.
